The ATTORNEY

UNITED STATES PATENT OFFICE

LESTER J. HYAMS, OF NEW YORK, N. Y.

ATTACHMENT FOR PENCILS AND LIKE INSTRUMENTS

Application filed September 24, 1930. Serial No. 483,995.

This invention relates to improvements in attachments for pencils and like instruments.

One of the objects of this invention is to provide an attachment for pencils and like instruments comprising a cap and means for mounting the same so that the cap will at all times be connected with the pencil and will be capable of being moved alternately from one end of the pencil to the other and is consequently capable of being utilized as a point protector when moved to the pointed end of the pencil and as an ornamental cap or rubber holder when moved to the other end of the pencil.

Still another object of my invention is to provide an attachment of the character specified with a clip formed integrally with said attachment.

Still other objects of my invention are to provide an ornamental or rubber-holding cap having a hinged connection with a slide member capable of being fitted to and moved longitudinally along the shank of the pencil to permit seating on opposite ends thereof, and to provide such a slide which will be capable of movement without marring the shank of the pencil.

With these and other objects in view, the invention comprises the combination of members and arrangement of parts so combined as to co-act and cooperate with each other in the performance of the functions and the accomplishments of the results herein contemplated, and comprises in one of its adaptations the species or preferred form illustrated in the accompanying drawings, in which:—

Fig. 1 is a view, partly in longitudinal section and partly in elevation, showing my attachment mounted on a lead pencil in point-protecting position;

Fig. 2 is a view, in elevation, showing my attachment also in point-protecting position but turned axially at right angles to the position shown in Fig. 1;

Fig. 3 is a view, in elevation, showing my attachment moved to its seat on the opposite end of the pencil;

Fig. 4 is a completely sectional view of a slight modification of my attachment show-

ing the same on a pencil in point-protecting position; and

Fig. 5 is a view, in elevation, similar to Fig. 2, of the attachment removed from the point and being moved along the shank of the pencil toward the opposite end thereof.

Referring now to these drawings, which illustrate a preferred embodiment of my invention, 1 indicates a pencil having a point 2 which it is desired to protect. In accordance with my invention, a cap 3 adapted to fit over the point of the pencil is provided with elongated legs 3', 3^a which are hinged to a slide member 4 which is fitted to the shank of the pencil and is movable along the same from one end thereof to the other. As illustrated, the slide 4 comprises a metal sleeve having ribs 4', 4' struck up at opposite ends thereof to reinforce the same and this sleeve also has struck up therefrom at opposite sides pivot cups 4^a, 4^a adapted to receive the heads 5^b of rivets 5 on which is mounted the legs 3', 3^a of the attachment, the rivet being passed through the extremities of the legs 3', 3^a and headed as at 5^a on the outer side thereof. I am thus enabled to provide a hinged connection between the cap member 3 and the slide member 4 in which the rivet will be raised from the surface of the pencil so as to prevent any marring thereof during the sliding movement of the sleeve on the shank of the pencil.

In the preferred embodiment of my invention, the cap member 3 at each side is provided with a notch 3^b conforming in outline to the point of the pencil so as to permit a quicker withdrawal of the pencil point from the cap when it is desired to move the same from the point end to the opposite end of the pencil, and this notch communicates with a side opening 3^d between the legs 3', 3^a and the slide 4.

In the preferred form of my invention illustrated, I combine with my attachment a spring clip 6 which, as illustrated, is formed integrally with the leg 3^a of the cap member 3 by striking up the metal forming said spring clip 6 from the metal of said leg 3^a, said clip being bent to have the free end 6' thereof disposed outwardly away from the leg 3 so as to permit the movement of

this free end over the edge of the pocket in the usual manner of fastening spring clips of this type.

In Figs. 1, 2, 3 and 5, I have shown the cap 3 provided with a mounting 3^c for a rubber 7 while in Fig. 4, I have shown an all metal cap completely enclosing the point or end of the pencil. In other respects the construction shown in Fig. 4 is similar to that shown and described in Figs. 1, 2, 3 and 5.

The operation of the device is as follows:

Assuming that the cap is mounted on the pointed end of the pencil as shown in Figs. 1, 2 and 4 and it is then desired to use the point, the cap is thereupon moved upwardly until the point is freed from the body of the cap whereupon the point is swung outwardly between the legs of the cap and the slide is then moved downwardly, as illustrated in Fig. 5, until the body of the cap reaches the end of the pencil when the cap and slide is again slid upwardly onto the end of the pencil, as shown in Fig. 3. Obviously, the point or shank may be moved in opposite directions through either of the side openings 3^a, 3^d and the cap may thereupon with the slide be moved along the shank to the other end of the pencil.

Having described my invention, I claim:—

1. An attachment for pencils and like instruments embodying, in combination, a cap adapted to be removably mounted on one end of a pencil, and an annular slidable member connected to said cap and movable along the shank of the pencil for permitting the removal of said cap from one end of the pencil and the mounting of the same on the other end thereof.

2. An attachment for pencils and like instruments embodying, in combination, a cap adapted to be removably mounted on one end of a pencil, and an annular slidable member movable along the shank of the pencil, said cap and slidable member having a hinged connection and side openings between the cap and slidable member to permit removal of the cap from one end of the pencil, the swinging of the said cap about the hinge connection with the slidable member and the movement with the slidable member toward the opposite end of the pencil to removably mount the cap thereon.

3. An attachment for pencils and like instruments embodying, in combination, a cap adapted to be removably mounted on one end of a pencil, and an annular slidable member movable along the shank of the pencil, said cap and slidable member having a hinged connection formed above raised bearing cups on the slidable member and said cap having side openings between the cap and slidable member to permit removal of the cap from one end of the pencil, the swinging of said cap about the hinge connection with the slidable member and the movement with the

slidable member toward the opposite end of the pencil to removably mount the cap thereon.

In witness whereof, I have signed my name to the foregoing specification.

LESTER J. HYMANS.
